UNITED STATES PATENT OFFICE

JACOB TELLER AND ARTHUR P. SCHULZ, OF NEW YORK, N. Y., ASSIGNORS TO TELLER CORPORATION, OF CHATTANOOGA, TENNESSEE, A CORPORATION OF TENNESSEE

DESIGN FOR A GAS OR ELECTRIC CABINET RANGE

Application filed September 16, 1931. Serial No. 41,130. Term of patent 7 years.

To all whom it may concern:

Be it known that we, JACOB TELLER and ARTHUR P. SCHULZ, citizens of the United States, and residents of New York city, in the county of New York and State of New York, have invented a new, original, and ornamental Design for a Gas or Electric Cabinet Range, of which the following is a specification, reference being had to the accompanying drawing, forming a part thereof.

The figure is a perspective view of the range showing our new design.

We claim:

The ornamental design for a gas or electric cabinet range, as shown.

JACOB TELLER.
ARTHUR P. SCHULZ.
